U.S. Appl. No. 29/366,124, filed Jul. 20, 2010 (59 pages).

Primary Examiner — Anhdao Doan(74) *Attorney, Agent, or Firm* — Popovich, Wiles & O'Connell, P.A.(57) **CLAIM**

The ornamental design for a landscaping block, as shown and described.

DESCRIPTION

FIG. 1 is a left and front perspective view of an embodiment of a landscaping block according to my new design;

FIG. 2 is a right and front perspective view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof; and

FIG. 8 is a bottom plan view thereof.

FIG. 9 is a left and front perspective view of an embodiment of a landscaping block according to my new design;

FIG. 10 is a right and front perspective view thereof;

FIG. 11 is a left side elevational view thereof;

FIG. 12 is a right side elevational view thereof;

FIG. 13 is a front elevational view thereof;

FIG. 14 is a rear elevational view thereof;

FIG. 15 is a top plan view thereof; and,

FIG. 16 is a bottom plan view thereof.
